UNITED STATES PATENT OFFICE.

JOHN BEAL, OF FENTON, MICHIGAN, ASSIGNOR OF ONE HALF TO CHARLES W. BUSH, OF SAME PLACE.

DETACHABLE HARNESS-ROSETTE.

SPECIFICATION forming part of Letters Patent No. 375,691, dated December 27, 1887.

Application filed March 28, 1887. Serial No. 232,660. (No model.)

To all whom it may concern:

Be it known that I, JOHN BEAL, a citizen of the United States, residing at Fenton, in the county of Genesee and State of Michigan, have 5 invented certain new and useful Improvements in Detachable Harness-Rosettes; and I do declare the following to be a full, clear, and exact description of the invention, such as will enable others skilled in the art to which it app-10 pertains to make and use the same, reference being had to the accompanying drawings, and to the letters and figures of reference marked thereon, which form a part of this specifica-15 tion.

15 My invention in rosettes relates more especially to that class used on bridles.

The object of said invention is to construct a rosette which will be cheap and durable, one that may be attached to the parts of a 20 bridle without sewing any of the parts of the bridle to it, and being so constructed that the rosette may be readily detached to allow the repairing of any of the parts connected thereto.

25 In my device the crown and frontstraps and the gag-runner are attached to the back face of the rosette, and by removing a single screw passing through the crown-strap into the rosette all of said parts become detachable, as 30 will be fully set forth; and my invention consists in the organization of parts, as herein-after set forth, and pointed out particularly in the claims.

In the drawings forming a part of this 35 specification, Figure 1 is a perspective of my device attached to the bridle of a horse. Fig. 2 is an enlarged perspective of the back face of the rosette, showing one end of the front strap attached, also the gag-runner, with 40 crown-strap removed. Fig. 3 is an enlarged perspective of the crown-strap, having like parts broken away. Fig. 4 is a section taken on dotted line *xx* of Fig. 2, showing the crown-strap attached. Fig. 5 is a section taken on 45 dotted line *ll* of Fig. 6, looking toward the left. Fig. 6 is a perspective of the back face of the rosette, showing the gag-runner attached for right-hand side of bridle and dotted position to show attachment of gag-runner for left-50 hand side.

As shown in the drawings, R represents the

rosette, which consists of the base circular disk of plate B, the front of which is covered by the polished plate B'. Its annular flange *a* overlaps the periphery of the plate B. The 55 covering-plate B' may be dispensed with. In such a case the outer plate, B, is to be ornamented or plated, as desired. I attach to the back face of the plate B a series of studs, *d*, standing at right angles to the plane of said 60 plate. The center of the plate B has a projecting hub or head, H, of a triangular form, with an internally - screw-threaded hole, *e*. (See Figs. 2 and 6.)

The front strap, F, is provided at each end 65 with a hole, *a'*, (see Fig. 2,) and is attached to the rosette by passing one of the lugs *d* through said hole, as shown in Fig. 2. The ends of the strap meet one of the triangular faces of the head H, as shown in Fig. 2, keeping it in position. The joining ends of the gag-runner *n* are provided with a hole, *a'*, to receive a lug, *d*, of the rosette, by which it is attached to the 70 rosette.

The front strap, F, is attached to the rosette 75 at nearly right angles to the gag-runner *n*, as shown in Fig. 2.

The crown-strip C is provided at each end with a cheek-billet, Z, and a throat-latch billet, *t*, which are formed from the crown-strip 80 by making the slit or cut O. (See Fig. 3.) The crown-strip is attached to the rosette (of which I employ two in a bridle) by crossing the back face at right angles to the front strap, F, and passing through the crown-strap a 85 screw, S, which is forced into the screw-threaded hole *e* in the head of the rosette. (See Figs. 3 and 4.)

It will be observed that the crown-strip being attached after placing on the studs the front 90 strap and gag-runner said front strap and gag-runner are prevented from coming off of the studs *d* by the pressure of the crown-strap C, and that the lug *d* presses against the crown-strap, thereby preventing the tilting of the rosette when the parts are attached. 95

To detach the parts, the screw S passing through the crown-strip is withdrawn, when the front strap, F, and the gag-runner may be removed from the studs to repair said straps 100 or to insert new ones. The parts attached to a rosette are held in position by a single screw,

and by its removal the rosette, or any or all of its attached parts, may be readily removed.

Having thus fully set forth my invention, what I claim as new, and desire to secure by 5 Letters Patent, is—

In a rosette, the combination of the plate B, having on its back face the screw-threaded hub and series of studs, the front strap and gag-rein runner each removably attached to a stud of

said plate, the crown-strap and screw S binding said parts together, as and for the purposes specified.

In testimony whereof I affix my signature in presence of two witnesses.

JOHN BEAL.

Witnesses:

JOHN THIEL,
C. W. BUSH.
